UNITED STATES PATENT OFFICE.

MEILICH MELAMID, OF FREIBURG, GERMANY, ASSIGNOR, BY MESNE ASSIGNMENTS, TO THE CHEMICAL FOUNDATION, INC., A CORPORATION OF DELAWARE.

METHOD OF TREATING HYDROCARBONS DERIVED FROM GAS-TAR.

1,362,127.

Specification of Letters Patent.

Patented Dec. 14, 1920.

No Drawing.

Application filed August 4, 1914. Serial No. 855,051.

To all whom it may concern:

Be it known that I, MEILICH MELAMID, a subject of the Czar of Russia, and resident of Freiburg, in the Grand Duchy of Baden, 5 Germany, have invented certain new and useful Improvements in Methods of Treating Hydrocarbons Derived from Gas-Tar, of which the following is a full, clear, and exact specification.

10 I have discovered that if gas tar, or the products of distillation thereof, are treated with phosphoric acid in a finely comminuted state and under constant agitation, a singular chemical action takes place, *i. e.*, a conversion of the tar, the tar oils or the tar derivatives in such a manner that hydrocarbons with high boiling point are converted into hydrocarbons with low boiling point and of a low specific weight. The agitation of the phosphoric acid in the mass can be effected either by mechanical means or by steam which is introduced during the distilling operation or which develops in the mass itself. According to the present 20 method the treatment of the hydrocarbons derived from tar with phosphoric acid takes place already at a low temperature.

The following examples serve to illustrate the variations in the method according to 25 the present invention:

Example 1.

100 kg. of a mixture of hydrocarbons derived from tar and obtained from the Freiburg gas works, and distilled in the usual manner without the addition of phosphoric acid, resulted in: up to 200° boiling 6.49% specific weight 0.950, from 200-230° boiling 16.53% specific weight 1.001, from 230-270° 30 boiling 7.76% specific weight 1.005, from 270-320° boiling 24.16% specific weight 1.005, pitch 44.3%.

Example 2.

45 If however the same quantity of hydrocarbons derived from tar was distilled with 25 kg. phosphoric acid under constant movement and in the presence of steam, the result was: up to 200° boiling 30.05% specific weight 0.897, from 200-230° boiling 9.00% specific weight 0.990, from 230-270° boiling 23.14% specific weight 0.992, from 270-320° boiling 14.08% pitch 22.05%.

When the oils treated under the stated 50 conditions are treated once more in the same

manner, they split again and hydrocarbons with still lower specific weight are produced, as is shown in the following example:

Example 3.

The distillate boiling up to 200° produced according to Example 2, is again treated with 25% phosphoric acid under the same conditions as before. The result is: up to 120° boiling 80% specific weight 0.860, up to 150° boiling 6% specific weight 0.867, up to 180° boiling 14% specific weight 0.880.

This example shows that all the hydrocarbons derived from tar and boiling up to 200° were converted into hydrocarbons with lower 70 boiling point and of lower specific weight.

Example 4.

When the distillate boiling from 200-270°, as produced according to Example 2 is again 75 mixed with 25 kg. phosphoric acid and distilled according to Example 2, the following surprising result is obtained: Below 120° boiling point 20% comes over and it has a specific gravity of 0.867, between 120° C. 80 and 180° C. boiling point, 25% comes over, which has a specific gravity of 0.884 and between that and 230° C. boiling point the remainder equal to 55% comes over and it has a boiling point of 0.965.

85 Hereby too it is proven, that all oils are converted into hydrocarbons with lower boiling point and of lower specific gravity. When further treated, the hydrocarbons of high specific gravity will always divide into 90 hydrocarbons with a lower boiling point and of a lower specific gravity.

From the foregoing it may be seen, that the distillate boiling up to 120° does not represent benzol, but that it is an entirely 95 novel product. Benzol of 90°, as at present on the market has a specific gravity or weight of 0.884, said novel product however, has a specific gravity of 0.860-0.866. This novel product has been used in an automobile equipped with the usual benzin gasifier. The motor worked very badly or not at all with this gasifier, when the above named benzol of 90° was employed, however, with said novel product, the working of the motor with said benzin gasifier was perfect and the exhaust gases were nearly odorless as compared to the exhaust gases of the benzin and of the benzol. However, it is still more interesting, that the motor with said novel 100 105 110

product developed a 10% higher velocity (i. e. efficiency) than with the best benzin. Furthermore said novel product proved to be about 12% more efficient than benzin of 5 a specific gravity of 0.720.

What I claim is:

1. A process for converting hydrocarbons of a high boiling point contained in tar into hydrocarbons of a lower boiling point by 10 treating tar containing such hydrocarbons with steam in the presence of phosphoric acid.
2. A process for converting hydrocarbons of a high boiling point received from tar into hydrocarbons of a lower boiling point by 15 treating such hydrocarbons with steam in the presence of phosphoric acid.
3. A process for converting hydrocarbons of a high boiling point contained in tar into

hydrocarbons of a lower boiling point by 20 treating tar containing such hydrocarbons with steam in the presence of phosphoric acid and at a temperature sufficient for the distillation of the produced lower boiling hydrocarbons.

25 4. A process for converting hydrocarbons of a high boiling point received from tar into hydrocarbons of a lower boiling point by treating such hydrocarbons with steam in the presence of phosphoric acid and at a 30 temperature sufficient for the distillation of the produced lower boiling hydrocarbons.

In testimony whereof I affix my signature in presence of two witnesses.

DR. MEILICH MELAMID.
